Primary Examiner — Mitchell I. Siegel*(74) Attorney, Agent, or Firm* — Finnegan, Henderson, Farabow, Garrett & Dunner, LLP**(57) CLAIM**

The ornamental design for a water ride, as shown and described.

DESCRIPTION

FIG. 1 is a perspective view of a water ride showing an embodiment of my new design;

FIG. 2 is a front view thereof;

FIG. 3 is a rear view thereof;

FIG. 4 is a right side view thereof;

FIG. 5 is a left side view thereof;

FIG. 6 is a top view thereof; and,

FIG. 7 is a bottom view thereof.

The portions shown in broken lines do not form part of the design. The lines consisting of short and long dashes do not form part of the design and are included solely for the purpose of illustrating the boundary of the design.
